CLAIM

The ornamental design for a filament-style LED array light, as shown and described.

DESCRIPTION

FIG. 1 is a front elevation view of a filament-style LED array light, showing my new design;

FIG. 2 is a top plan view thereof;

FIG. 3 is a bottom plan view thereof; and,

FIG. 4 is a top perspective view thereof.

The broken lines represent portions of the light which form no part of the claimed design.
